STEADY REST FOR LATHES

Waldemar Chester Martens, Stanton, Del.

Application December 21, 1945, Serial No. 636,423

1 Claim. (Cl. 82—39)

1 This invention relates to a steady rest for lathes, and more particularly to such a device for supporting and steadyng work operated upon by a lathe or similar tool.

A primary object of the invention is the provision of an improved steady rest for lathes characterized by extreme adaptability and relative freedom from friction in rotation.

A further object of the invention resides in the provision of an improved chuck for such a rest characterized by a plurality of jaws, certain of which are universally movable for quick setting of the device, and others of which are individually movable for extremely accurate work.

A further object of the invention resides in the provision of an individually movable jaw in the chuck of the device, whereby off-center work may be readily turned.

Still another object of the invention is the provision of an improved tool of the character to be hereinafter described which may be readily adapted for turning cams or similar work, or which may be utilized for the steadyng and holding of straight turned work.

A further object of the invention is the provision of such a device which may be equally advantageously utilized on square stock or the like for holding the same steady and without vibration.

Other objects reside in the combinations of elements, arrangements of parts, and features of construction, all as will be more fully pointed out hereinafter and disclosed in the accompanying drawings, wherein there is shown a preferred embodiment of this inventive concept.

In the drawings:

Figure 1 is a side view, partially in elevation, and partially in section, showing the main head or housing of the device, the chuck being indicated in dotted lines, and certain associated portions of the lathe bed also being indicated in dotted lines.

Figure 2 is a front elevational view of the housing of Figure 1, the chuck being removed, and certain concealed portions thereof being indicated in dotted lines.

Figure 3 is a front elevational view of the chuck adapted to be associated with the housing.

Figure 4 is a side elevational view of the device shown in Figure 3.

Figure 5 is an enlarged fragmentary sectional view disclosing the operation of certain individually movable jaws on the chuck of Figure 3.

Figure 6 is a fragmentary enlarged sectional

2 view disclosing the mechanism for the simultaneous or universal movement of certain of the other jaws of the mechanism of Figure 3.

Similar reference characters refer to similar parts throughout the several views of the drawings.

Referring now to the drawings, and more particularly to Figures 1 and 2, there is generally indicated at 10 a main frame or housing for the steadyng device. The frame includes a flat base portion 11 provided with recesses 12 in the rear thereof to accommodate nuts 13 securing bolts 14 provided with enlarged heads or lugs 15 adapted to hold the housing on a lathe bed or way 16. The housing 10 has positioned centrally thereof a circular aperture within which is mounted for rotation a spindle 17 including a tapered flange portion 18 at the rear thereof adapted to engage roller bearings 19 which are journaled on a bearing ring 20 positioned in a suitable flange interiorly of the housing. A second bearing ring 20 is also positioned in an appropriate groove and carries roller bearings 22 adapted to coact with a bearing ring 23 surrounding the forward portion of the member 17.

An apertured bearing retaining plate 25 is provided at the rear face of the device and has interiorly positioned thereof a flange 26 coacting with an appropriate groove 27 in the rear of member 17, which serves as a grease-retaining ring, grease being adapted to be introduced to the device through a conventional grease cup 28. The plate 25 is apertured, at suitably spaced intervals, and is secured to the housing 10, as by means of screws 29. A front bearing-retaining plate 30 is also provided and is secured, as by means of screws 31, to the front of the device, fitting in a suitable recess in the face of the device.

In the upper portion of the device a tapered hole 32 is provided adapted to accommodate a centering pin. The lower portion of the housing 10 has projecting forwardly therefrom a flange 33 channeled, as at 34, to accommodate for rotation therein a portion of a chuck generally indicated at 35, and to be more fully described hereinafter.

The forward portion of the member 17 extends outwardly of the housing 10 and is provided with a chamfered forwardly extending portion 36 positioned around which are a plurality of pins 37 adapted to engage appropriate apertures in the chuck 35 for securing the same to the member 17 for rotation therewith. It is to be understood that the work spindle carrying the tool or work

is adapted to extend through the centrally positioned aperture 38 (see Fig. 2) extending through the spindle 17.

Referring now to the chuck 35, as best shown in Figures 3 to 6, inclusive, it will be seen that the same comprises an annular body 39 provided with a centrally positioned aperture 40, and as best shown in Figures 5 and 6, the rear portion of the aperture 40 is tapered or beveled, as at 41, to engage the corresponding taper of the portion 36 of the spindle 17. As best shown in Figure 6, one of the apertures 42 for the accommodation of the pins 37 is also disclosed.

Positioned radially about the aperture 40 are a plurality of jaws 43 comprising one set, the jaws of which are substantially equally spaced angularly around the chuck and interposed between which are a plurality of additional jaws 44 of a different type constituting a second set, the jaws of which are substantially equally spaced from each other and from the jaws of the first set. The jaws 43 are adapted to be moved simultaneously, in a manner to be hereinafter described, for the quick setting up of the apparatus and the work contained therein, while the jaws 44 are adapted to be moved and set individually for extremely accurate work, or for the positioning of a tool or piece of work off-center of the device.

Referring in detail now to the method of moving the jaws 43, it will be seen, as best shown in Figure 6, that the rear of the chuck is recessed peripherally, as indicated at 45, and within the recess 45 is positioned a disc 46 toothed on its outer surface, as indicated at 47, and having helical ridges 42 on its inner side engaging corresponding teeth 48 carried by the rear surface of each of the jaws 43. It is to be noted that the jaws 43 are radially movable in appropriate slots 49 cut into the face of the chuck. The disc 47 is adapted to rotate on a ring 50 carrying bearings 51, and is held in position by a back plate 52 and a retaining ring 53 secured to the chuck, as by means of a set screw 54. The rear face of the disc 46 is provided with a ring gear 55 adapted to be engaged by a pinion 56 mounted on a shaft 57 supported by a bracket 58 secured to the outer rim of the chuck, as by means of a set screw 59. The upper extremity of the shaft 57 is squared, as indicated at 60, and extends into an aperture 61 extending through the rim of the chuck. It will thus be seen that by means of an appropriate tool, the shaft 60 may be turned, which in turn rotates the disc 46, thus varying the relative position of all the jaws 43 simultaneously, in order to hold the work in appropriate position within the aperture 40.

Referring now to the individually movable jaws 44, which are movable in radial slots 65 in the chuck face, it will be seen that the rear surface of each is provided with teeth forming a rack 66 adapted to be engaged by a screw or worm 67 positioned in an appropriate recess 68 within the chuck body, and journaled for rotation on an axle 69. The upper portion of the screw 67 is provided with a squared extremity 70 which extends through a suitable aperture 71 adjacent each jaw, and it will thus be seen that upon the

application of an appropriate tool to the squared end 70, and rotation of the screws 67, that each jaw 44 may be individually moved to the extent desired.

Now, from the foregoing it will be seen that there is herein provided an improved steady rest for lathes or similar tools provided with a plurality of simultaneously movable jaws for the quick setting up of work, and correspondingly provided with a plurality of individually movable jaws by means of which work may be set off-center if desired, or adjusted to extremely accurate tolerances, which accomplishes all the objects of this invention, and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

In a lathe steady rest, a chuck support comprising an annular housing having a flat bottom surface adapted to rest upon a lathe bed, and having two annular grooves disposed one in each end thereof, two beveled bearing races disposed one in each groove and having their bearing faces oppositely and outwardly inclined, a hollow, cylindrical spindle having an integral, beveled bearing race on one end thereof journaled in said housing, a separate beveled bearing race on the opposite end of said spindle, anti-friction rollers between associated bearing races, and two annular bearing retaining rings removably secured one to each end of said housing and overlying the outer edges of the corresponding bearing races to retain said races and said spindle in operative position in said housing, said spindle having a chamfered annular portion on one end thereof providing a mounting seat for a chuck, and angularly-spaced pins projecting from said chamfered end of said spindle to support a chuck on said mounting seat.

WALDEMAR CHESTER MARLENS.
